UNITED STATES PATENT OFFICE.

ALFRED BORN, OF MAGDEBURG, GERMANY, ASSIGNOR TO THE FIRM FRIED. KRUPP
GRUSONWERK AKTIENGESELLSCHAFT, OF MAGDEBURG-BUCKAU, GERMANY.

EXTRUSIONS PRESS.

Application filed May 10, 1927, Serial No. 190,363, and in Germany May 18, 1926.

My invention relates to plastic metal working presses known as "extruding" presses, in which the metal, preferably in a heated state, is forced through a die for producing 5 solid or hollow articles as bars, tubes etc.

The invention relates to extruding presses of special type comprising a die, a stationary member for supporting the die, a movable container for receiving the metal ingot 10 and a plunger for forcing the metal through the die.

Heretofore most presses of this type were designed in such wise as to perform so-called "direct pressing" operations, viz, forcing the 15 metal through the die by means of a solid ram attached to the front of the plunger, said ram being pushed into the container while the latter was at rest, thus literally "extruding" the metal from the container.

As known to those familiar with the operation of metal presses of this kind, the extrusion of the metal ingot from the container offers considerable frictional resistance to the plunger and its ram respectively in addition to the resistance offered by the die 25 proper.

As a matter of fact the pressure exerted upon the metal ingot must first permeate its 30 whole length which first causes a considerable compression of its molecules before the metal is actually extruded through the die, and thus consumes a relatively high proportion of power which is lost for the extruding action proper.

The object of my invention is to provide 35 improved means for metal working presses of the direct pressing type set forth, by which the pressing process can be performed—whenever desired—also in the so-called indirect manner viz, pushing by means of the plunger alone the metal ingot and the container in which it rests simultaneously ahead against and over the die respectively. In this case much less power is 40 required for the pressing operation and another still more important advantage is achieved inasmuch as practically all the scale and other impurities formed at the surface of the ingot, will automatically be retained within the receiver and will not contaminate the extruded metal.

Metal presses designed but for performing 45 the indirect pressing process as outlined above are already known in practice and are 50 structurally distinguished from those for

the direct pressing process therein that the die is carried on a die holder protruding from the frame of the press.

In other words the object of my invention consists in providing improved means for 60 presses of the types under consideration in such wise that one and the same press can be conveniently adapted and used both for direct and indirect pressing operations, thereby extending considerably the field of 65 its application in practice and entailing— whenever used for indirect pressing—among other important advantages great economy in power consumption and producing goods of high quality. 70

Other objects of the invention will appear incidentally hereinafter.

The nature and scope of my invention is briefly outlined in the appended claims and will be more fully understood from the following specification taken together with the accompanying drawing. 75

Fig. 1 shows in longitudinal section an improved metal extruding press designed according to this invention and temporarily 80 adapted for performing so-called direct pressing operations;

Fig. 2 shows in longitudinal section the same improved press being temporarily 85 adapted for performing indirect pressing operations as specified hereinbefore.

In both figures 1 designates the stationary frame of the press at one side of which the hollow body 2 is mounted while at the other side the hydraulic cylinder 3 is arranged in 90 which the plunger 4 is movable to and fro.

The container 5 is carried on guide members 6 and 6^a and is adapted to be shifted along said guide members by hydraulic force 95 viz plungers 7, 7^a as seen in the drawing.

According to this invention the ram 8 is made hollow and is designed at its rear portion so as to be capable of being attached to the plunger 4 as well as to the hollow body 2 of the frame preferably by one and the 100 same fastening device. In the embodiment of my invention shown by way of an example in the drawing a clamping ring 9 is provided for securing the hollow ram 8 to both members 4 and 2 of the press. As seen in Fig. 105 1 at the plunger 4 a recess and a bearing plate 8^a are provided for holding the ram 8 centrally in its proper place at the plunger 4. The head portion of the ram 8 is designed so as to be capable of holding either a 110

pressure plate 10, as shown in Fig. 1, serving as a lid to the hollow ram, or of holding the die 11, as shown in Fig. 2.

In Fig. 1 the die 11 is shown to be attached 5 to the stationary hollow body 2 of the press by means of a fastening member 12 of an- nular shape.

The front face of the hollow body 2 is 10 designed so that either the annular member 12 for fastening the die 11 or the clamping ring 9 for holding the hollow ram 8 can be easily attached thereto, as indicated in Figs. 1 and 2 respectively.

Whenever the press is to be used for indi- 15 rect pressing operations—as shown in Fig. 2—a pressure plate 13 is to be inserted into the recess of the plunger 4 so as to replace the bearing plate 8 referred to above.

Various changes and modifications may be 20 made in the design, assemblage, and cooperation of the principal component parts of plastic metal working presses of the type specified above, without substantially departing from the scope of the appended claims 25 and deviating from the spirit of my invention.

It is obvious to those skilled in the art that metal presses showing the salient features of this invention may be provided with a

mandrel for the production of hollow articles 30 such as tubes and the like.

What I claim is:

1. In a plastic metal working press, a stationary hollow frame body, a plunger, a container, a hollow ram, means for securing 35 said ram to said hollow frame body, means for securing said ram to said plunger, a die, means for securing said die to said ram, and means for securing said die to said hollow frame body, whereby said press may be used 40 for either direct or indirect pressing.

2. In a press as set forth in claim 1, a de- 45 tachable lid adapted to be applied to the head-portion of said hollow ram.

3. A press according to claim 1 in which 45 said means for securing said ram to said hollow frame body and to said plunger com- prises a detachable clamping ring.

4. In a press as set forth in claim 1, a bearing plate and a pressure plate, said 50 plunger having a recess adapted to receive said bearing plate or said pressure plate, said bearing plate being recessed to receive the base end of said ram.

The foregoing specification signed at Ber- 55 lin this 21st day of April, 1927.

ALFRED BORN.
